UNITED STATES PATENT OFFICE

148,336

DESIGN FOR A CASING FOR AN ELECTRICAL TIMER

John W. Speaker, Milwaukee, Wis.

Application October 24, 1946, Serial No. 134,192

Term of patent 14 years

(Cl. D26—5)

To all whom it may concern:

Be it known that I, John W. Speaker, a citizen of the United States, residing at Milwaukee, in the county of Milwaukee and State of Wisconsin, have invented a new, original, and ornamental Design for Casing for an Electrical Timer, of which the following is a specification, reference being had to the accompanying drawings, forming part thereof.

Figure 1 is a perspective view of a casing for an electrical timer showing my new design;

Figure 2 is a front elevational view thereof;

Figure 3 is a top plan view; and

Figure 4 is a view in side elevation.

The characteristic features of my design reside in the portions shown in full lines. The sides of the timer casing are identical in appearance. The back and bottom are plain.

I claim:

The ornamental design for a casing for an electrical timer, as shown and described.

JOHN W. SPEAKER.
